Specification for Design.

Patented May 30, 1922.

Application filed December 27, 1921. Serial No. 525,260. Term of patent 14 years.

To all whom it may concern:

Be it known that I, EUGENE C. HEILHECKER, a citizen of the United States, residing at Bristol, in the county of Bristol and State of Rhode Island, have invented a new, original, and ornamental Design for a Sole of a Rubber Boot or Shoe, of which the following is a specification, reference being had to the accompanying drawing, forming a part thereof, wherein—

Figure 1 is a side elevation of a boot show-

ing my new design, the design being confined to the sole portion thereof.

Figure 2 is a bottom plan view of same.

I claim:

The ornamental design for a sole of a rubber boot or shoe, as shown.

Signed at Bristol, county of Bristol, State of Rhode Island, this 19th day of December, 1921.

EUGENE C. HEILHECKER.
